TELEGRAPHIC PRINTING APPARATUS

Clyde J. Fitch, Endicott, N. Y., assignor to International Business Machines Corporation, New York, N. Y., a corporation of New York

Application March 17, 1945, Serial No. 583,227

11 Claims. (Cl. 178—4)

1

This invention relates to a control mechanism capable of operating a telegraph printer having a larger number of keys than can be selected by all the possible different combinations of the code used.

On many commercial telegraph lines, a five unit code is used, known as the Baudot code. This code affords only thirty-one usable combinations, which is not enough to operate a page printer having a standard typewriter keyboard. Accordingly, a particular object of the invention is to provide a control mechanism capable of operating in response to five unit code, to control a printer having a capacity equivalent to a standard typewriter keyboard, including both capital and small letters.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a diagrammatic view of a tape reader for reading the perforated tape.

Fig. 2 is a vertical sectional view of a portion of a telegraph printer which may be operated under control of the tape reader shown in Fig. 1.

Fig. 3 is a vertical sectional view of a portion of the permutation mechanism by means of which the keys of the printer are selectively operated.

Fig. 4 is a detail view of the carriage return key.

Fig. 5 is a section of tape illustrating the five unit code employed.

Fig. 6 is a timing diagram of the tape reader contacts.

Fig. 7 is a diagram of the keyboard of the printer.

Fig. 8 is a circuit diagram of the entire apparatus.

A telegraph printer control mechanism in accordance with the invention may be operated directly from signals received telegraphically, or by means of a perforated tape. For the purpose of illustration, a tape controlled telegraph printer is shown in the present application. The tape may be one prepared by a telegraphic receiving punch operating in response to signals from a tape transmitter controlled by a tape prepared by a typewriter tape punch, of the kind shown in my copending application, Serial No. 581,609, filed March 8, 1945.

The tape reader

The tape reader shown in Fig. 1 is similar to the one disclosed in Patent 2,320,788. The tape 10 is fed from a reel (not shown) over a guide roller 11, a tape feeler and guide 12, through the slot of a sensing pin guide block 13, over a

5 sprocket 14, and thence to a take-up reel (not shown). The tape feeler 12 is adapted to open contact TC if tension on the tape fails. In the sensing pin guide block are five sensing pins 15 similar to the one shown at 15 in Fig. 1. The sensing pins are distributed across the tape in line, respectively, with the five different code positions 1, 2, 3, 4, 5 (Fig. 5). Associated with each sensing pin is a pin contact, such as the contact 10 PC5, comprising a stationary contact spring 16 and a movable contact spring 17 having an insulating rod 18 at its end bearing upon the end of the related sensing pin 15. During certain times in the cycle of operation of the tape reader, the sensing pins are allowed to move against the tape, under the action of the movable contact springs. Those sensing pins which find a hole in the tape move far enough to permit the contact points on the contact springs to engage. 15 The different pin contacts will later be referred to as PC1, PC2, PC3, PC4, and PC5.

The sensing pins are controlled by a fin 19 on a shaft 20, which extends to the rear, as represented by the dot and dash line 20', and has 25 fixed to it a three-armed lever 21. The leftwardly directed arm of the lever 21 carries a roller 22 at its end bearing upon a cam 23 fixed to a shaft 24, which extends to the rear as indicated by dot and dash line 24', and has fastened to it a pulley 25 constantly driven by a motor RM through a belt 27. The rightwardly directed arm of the lever is normally latched by an armature plate 30 pivoted at 31 and pulled toward the left by a spring 32. A latch magnet LM is energized, in 35 a manner to be described, to withdraw the latch plate from the arm. When this occurs the arm rocks clockwise, then counterclockwise, following the contour of the cam 23. When it rocks clockwise the fin 19 releases the sensing pins and 40 allows them to engage the tape. When it rocks counterclockwise, the pins are withdrawn from the tape.

The tape feed sprocket shaft 33 extends to the rear, as indicated by dot and dash line 33', and has fixed to it a feed ratchet wheel 34. Cooperating with the ratchet wheel 34 is a feed dog 35, articulated to an arm 36, which is fixed to a pivot shaft 37. The arm 36 has journaled upon it a roller 38 bearing against a second cam 39 on the 45 shaft 24. Normally the arm 36 is latched by means of an arm 40 extending rigidly from the pivot shaft 37 and overhanging a latching dog 41 pivoted at 42 on the upwardly extending arm of the lever 21. When the latch magnet is energized and the three-armed lever 21 rocks clockwise, the latching dog 41 is removed from the arm 40 and the feed arm 36 is allowed to rock clockwise, under a pull of spring 43, following the contour of cam 39, then counterclockwise, 50 as the high part of the cam passes under the

small roller 38. The first movement allows the feed dog to ratchet over a tooth of the ratchet wheel, with which it is held in contact with a spring 44. The second movement of the feed arm feeds the ratchet wheel forward by one tooth, at the end of which movement the dog engages a cam block 45, which limits its movement and also locks the feed ratchet wheel against overthrow. The shaft 33 also has fixed to it a toothed detent wheel 49 with which cooperates a small roller 46 on a detent arm 47 pivoted at 48 and pulled downward by a spring 50. The latching dog 41 is urged in counterclockwise direction about its pivot 42 by a small spring 51, so that a pin 52 thereon normally engages the upper end of the arm 21. As explained in the above mentioned Patent 2,320,788, the timing is such that the three-armed lever 21 is restored to normal position before the feed arm 36 completes its feed stroke. Consequently, the latch dog 41 first strikes the end of the latch arm 40 and does not move under the latch arm until the end of the feed stroke.

The shaft 24 also has fixed to it five contact operating cams 55, 56, 57, 58 and 59 with which are associated, respectively, five contacts C1, C2, C3, C4, C5, to be referred to later in connection with the circuit diagram.

The printer

The illustrative machine comprises a typewriter having a keyboard 60 (Fig. 2), the keys of which are subdivided into two zones, as indicated by the dot and dash lines in Fig. 7. Zone 1 includes all of the letters of the alphabet, except the letters *k* and *l*. Zone 2 includes the letters *k* and *l*, the numbers, the TAB key and various symbols and punctuation marks. In addition, the keyboard includes a carriage return key, an upper case key, and a space bar, these keys being outside of both zones.

As shown in Fig. 5, the twenty-four letters of the alphabet in zone 1 use the standard Baudot code combinations. This is also true of the space, carriage return, line feed, figures shift (upper case) and letter shift (lower case). The code combinations formerly used for letters *k* and *l* are used, respectively, for the zone 1 and zone 2 shift signals. The zone shift signals occur when there is a transfer from one zone to the other, that is to say, when a zone 2 character follows a zone 1 character, the zone 2 shift signal will be inserted between them, and when a zone 1 character follows a zone 2 character, the zone 1 shift signal will be inserted between them.

The type bar actuating mechanism 61 (Fig. 2) is of the type disclosed in Patent 1,873,512 and has a permutation bar control mechanism 62 for operating its keys of the kind disclosed in Patent 2,165,247. The type bars (not shown) are actuated by a power driven roller 63. A cam 64 is provided for each type bar and each cam is journaled on one arm of a related bell crank lever 65 pivoted on a stationary rod 66, the other arm of the bell crank lever 65 being operatively connected with one arm of a related bell crank lever 67 by means of a link 68. The other arm of lever 67 is connected to the related type bar (not shown) in well known manner (see Patent 1,873,512).

The lever 65 is actuated by the cam 64 when the latter is made to engage the driven roller 63 by operation of a related key lever 76. The cam 64 is engaged by a spring pressed arm 70 which tends to turn it into contact with the roller 63,

but is normally restrained by a stop 71 on a lever 72 pivoted on the bell crank 65, which stop normally stands in the path of a lug 73 on the cam. When the lever 72 swings to move its stop 71 out of the path of the lug 73, the arm 70 swings the cam into engagement with the power roller, to be actuated thereby, to swing the bell crank 65 to actuate its connected mechanism.

The lever 72 has an arm 74 which is provided with an offset projection at its end, which projects laterally through an opening in the bell crank lever 65 and between the tangs of the bifurcated lower end of an arm 75 of the key lever 76 pivoted on the common rod 77. Depression of the key lever will rock the lever 74 and release the cam 64 as described.

Each key lever 76 is connected by a link 78 to a related control lever 79 pivoted on a common rod 80 and urged downward by a spring 81 against a set of six revoluble permutation bars 82, bearing the individual numbers 1, 2, 3, 4, 5, 6. In line with the control lever 79 the permutation bars have slots 83, the slots on the bars 1, 3 and 5 being on the top side, while those on the bars 2, 4 and 6 are on the bottom side. If the bars 2, 4, and 6 are revolved while the bars 1, 3 and 5 remain stationary, all the bars will present slots to the particular control lever 79 shown in Fig. 2, which will therefore rock downward under the influence of the spring 81, actuating the related key lever 76. The arrangement of the slots 83 aligned with each of the control levers 79 is different, so that by rotating different combinations of the permutation bars 82, different keys will be actuated.

The driving and control means for the selective rotation of the permutation bars has substantially the same construction as disclosed in Patent 2,165,247. Under the permutation bars is a drive shaft 85 driven by a motor (not shown). The shaft 85 has a driving gear 86 fixed to its left end and a similar gear at its right end, which does not show in the drawings. The gear 86 meshes with a gear 87 fixed to a short shaft 88 journaled in bearings 89, so as to be concentric to permutation bar 3. The gear 87 meshes with gears 90 and 91 fixed to short shafts (not shown) similar to the shaft 88, but concentric to the permutation bars 1 and 5, respectively. At the opposite end of shaft 85 the arrangement is similar but the gear corresponding to gear 87 is fixed on a short shaft concentric to permutation bar 4, while the gears corresponding to gears 90 and 91 are fixed to short shafts concentric to permutation bars 2 and 6.

The short shaft 88 has fixed to its inner end a ratchet toothed drive wheel 92 positioned to be engaged by a tooth 93 on a sliding dog 94 of a clutch 95 mounted on the end of the related permutation bar 3. As more fully disclosed in Patent 2,165,247, the engagement of the tooth 93 is controlled by a bell crank lever 96 pivoted at 97 and having an armature 98 attached thereto operated by a code magnet M3. Each of the other short shafts similar to 88 has the same kind of clutch means for connecting it to the related permutation bar. There are five additional code magnets, to be referred to later as M1, M2, M4, M5, and M6, controlling the respective clutches.

The arrangement of the slots 83 in the permutation bars is such that rotation of different combinations of the permutation bars releases different keys for operation. All of the keys in zone 2 require rotation of the No. 6 permutation bar, 75 while all the keys in zone 1 require this bar to

remain stationary. This permutation bar, therefore, acts as a zoning member, to route the signals to the different zones. The control levers which respond to the carriage return code, the line feed code, and the space code are cut out over the No. 6 permutation bar, so that their operation will not be affected by it. For the rest of the permutation bars, the arrangement of the slots is indicated by the respective five position code combinations of the tape in Fig. 4, that is, a hole in the tape will always cause the related permutation bar to rotate; therefore, the appertaining slot will face downward.

A shift solenoid SHS (Fig. 2) has a plunger 92 articulated to a lever 93 connected by a link 94 to the upper case key UC. The key UC operates a basket shift mechanism (not shown) similar to that disclosed in Patent 1,945,097. Accordingly, when the solenoid SHS is energized, the type basket shifts to the upper case position and remains in that position until the solenoid is de-energized, when it shifts back to lower case position.

Fig. 4 shows a detail of the carriage return key CR. The lever 76a of the key CR is overhung by a flap 96 on a keyless lever 76b. The key lever 76a is associated with a cam mechanism for operating a carriage return mechanism such as shown in Patent 2,104,559. The cam mechanism is similar to those shown in Fig. 2, except that the cam is of single lobe shape, instead of the double lobe shape of cams 64. The lever 76b has no cam mechanism of its own, but acts through the key lever 76a. Each of the levers 76a and 76b has a control lever 78 (Fig. 2) connected to it by a link 78. The control lever for the key lever 76a responds to the carriage return code 4, while the control lever for the keyless lever 76b responds to the line feed code 2.

Operation

Referring to Fig. 8, the apparatus comprises a typewriter represented by dot and dash lines 98, a tape reader represented by dot and dash lines 99, and a relay gate located therebetween. When the apparatus is plugged to a source of power, represented by + and - in Fig. 8, and the main switch MS on the typewriter is closed by operation of switch lever 120 (Fig. 7), circuits are completed from the positive wire 100, through the typewriter motor TM, the permutation unit motor PM, and the tape reader motor RM, to the negative wire 101, setting said three motors in operation. When the tape has been inserted in the tape reader, the machine is started by pressing the start button STR. The cams operating cam contacts C1-C5 are continuously running whenever the motor RM is in operation. When contact C4 closes at 45° (Fig. 6), a circuit is completed from wire 100, through said contact, wire 102, the start contact STR, the pick-up coil of relay R27 to wire 101, energizing said relay. Contacts R27a close, completing a circuit through the holding coil of relay R27 from wire 100, through tape contact TC, which will be closed whenever the tape is present with the proper tension in the tape reader, stop contact STP, contact R27a, the holding coil of relay R27, to the wire 101. The contacts TC and STP are shunted by the contact C1, which opens between 210° and 316° of the 70 cycle to test the holding circuit of relay R27.

Contacts R27b and R27c close, preparing the circuit of the latch magnet LM and the circuit to the permutation code magnets M1-M6, respectively. At 333° the cam contact C5 closes, com-

pleting a circuit from wire 100, through said contact, the latch magnet LM, a series of normally closed contacts R15c, R16c, R17c, the contact R27b, resistance 103, to wire 101, energizing the latch magnet. The armature 30 (Fig. 1) releases the three-armed lever 21, which rocks clockwise, allowing the tape feed dog 35 to ratchet back over one tooth of the wheel 34 and the sensing pins to test the tape between 33° and 246° of the following cycle. After the sensing pins have been withdrawn from the tape by the clockwise rocking of the three-armed lever 21, the feed dog 35 feeds the tape one step. The latch magnet LM will now be energized each time the contact C5 closes, near the end of the cycle, so long as the latch magnet circuit remains prepared. During this time the step-by-step tape sensing and tape feeding will continue.

It will now be assumed, to take the simplest case first, that the machine has been in operation in zone 1 and another character in zone 1 is to be printed. Suppose it is the character *a*, having the code 12. At 33° the sensing pins test the tape. At 45° the cam contact C4 closes, completing a circuit from wire 100, through contact C4, the pin contacts PC1 and PC2, the pick-up coil of code relays R1 and R2, to wire 101, energizing said code relays. Contacts R1a and R2a close and at 81° cam contact C2 closes, completing a holding circuit from wire 100, through contact C2, contacts R1a and R2a, the holding coils of relays R1 and R2, to the wire 101. Contacts R1b and R2b close and at 144° contact C3 closes, completing a circuit from wire 100, through contact C3, wire 104, the series of normally closed contacts R14a, R13a, R12a and R11a, the contacts R27c now closed, contacts R1b, R2b, normal contact R20, and code magnets M1, M2 to wire 101, energizing said code magnets and causing the printer to print the letter *a*.

At 207° the contact C4 opens, followed by the opening of the pin contacts PC1 and PC2 at 246°. At 250° cam contact C3 opens, deenergizing the code magnets M1 and M2 and at 335° cam contact C2 opens, dropping out the code relays R1 and R2 and restoring the circuit to normal condition.

Zone 2 shift.—Before the first character code of every message there will appear a zone shift signal. Suppose the zone shift signal at the beginning of the message is the zone 2 shift signal 25 followed by the code 24, representing the number 5. When the sensing pins sense the zone 2 shift signal in the tape, and when the cam contact C4 closes at 45°, circuits are completed, as previously described, through the code relays R2 and R5, which will be energized and then held through their contacts R2a and R5a, upon closure of the contact C2 at 81°. At the same time, a circuit is extended through wire 105, normal contacts R1c, transferred contacts R2c, normal contacts R3c and R4c, transferred contacts R5c, relay R14 to the negative wire 101, energizing said relay. Contacts R14a open, to prevent a circuit from being completed to the code magnets when the contacts C3 close later in the cycle. Contact R14b closes, completing a circuit from wire 100, through wire 106, contact R14b, the pick-up coil of relay R19 to the negative wire 101, energizing said relay. Contact R19a closes, completing a holding circuit from wire 106, through normally closed contact R13b, contact R19a, the holding coil of relay R19 to the wire 101. Contact R19b closes, preparing a circuit to code magnet M6. At 335° cam con-

tact C2 opens, dropping out the relays R2, R5 and R14. Contact R14a closes.

On the next cycle, the pins sense the code 24 representing the number 5. The code relays R2 and R4 are energized in the manner previously described, and the contacts R2b and R4b close. At this time the circuits are prepared to the code magnets M2, M4 and M6, the relay R19 remaining energized from the previous cycle. At 144°, the contact C3 closes, completing the normal circuit through wire 104 and the code magnets M2, M4 and M6 which are energized and cause the printer to print the number 5. As long as operation continues in zone 2, the code magnet M6 will be energized in each cycle, together with such combinations of the code magnets M1—M5, as the successive code combinations in the tape call for. Any one combination of magnets M1—M5 will permit operation of either of two keys, one in zone 1, the other in zone 2. Magnet M6 determines the zone. Thus, so long as the relay R19 remains energized, all signals will be routed to zone 2.

Zone 1 shift.—When the first character code representing a character in zone 1 appears in the tape, it will be preceded by the zone 1 shift signal 1, 2, 3, 4. When the pins sense this signal, the relays R1—R4 are energized and, when the contact C2 closes, a circuit is completed through wire 105, transferred contact R1c, contact R2d now closed, transferred contact R3e, contact R4f now closed, normal contact R5f, the coil of relay R13 to wire 101, energizing said relay. The contact R13a opens immediately, breaking the normal circuit through wire 104 and preventing the code magnets from being energized during this cycle when the contact C3 closes. Contact R13b opens, dropping out the relay R19, whose contact R19b opens, disabling the circuit to the code magnet M6. When the contact C2 opens at 335°, the relays R1—R4 and R13 are deenergized and contact R13a closes.

Suppose that the next code sensed in the tape is 24, representing the letter *r*. When the contact C4 closes, the relays R2 and R4 are energized. Closure of contact C3 completes the normal circuit through wire 104 and contacts R2b and R4b to the code magnets M2 and M4, energizing said magnets and causing the printer to print the letter *r*. It will be noted that, whereas the 24 code previously caused the number 5 to be printed, following a zone 2 shift signal, this time the code 24, following the zone 1 shift signal causes the letter *r* to be printed. The relay R19 functions as a supervisory means having two stable conditions, between which it alternates in response to the two zone shift signals.

Case shift.—Each zone includes upper case characters as well as lower case characters. The upper case characters are reached in the normal way, by operation of the case shift key UC. As in standard telegraph work, this operation is initiated by the so-called "figures shift" core 1245. When this code is read by the sensing pins, the relays R1, R2, R4 and R5 are energized. When contact C2 is closed, a circuit is completed through wire 105, transferred contacts R1c, contacts R2d, now closed, normal contact R3e, contact R4e now closed, transferred contact R5e, coil of relay R12, to the wire 101, energizing said relay. Contact R12a opens, disabling the normal circuit to the code magnets. Contact R12c closes a circuit directly from wire 106, through the shift solenoid SHS to wire 101, energizing said solenoid, which pulls down and holds the

case shift key UC. Also, contact R12b closes, completing a circuit from wire 106, through said contact, the pick-up coil of relay R18, to wire 101, energizing said relay. Contact R18a closes, completing a holding circuit for relay R18 from wire 106, through normally closed contact R11b and contact R16a. Contact R18b closes, completing a holding circuit from wire 106, through said contact and a resistance 107 to the shift solenoid SHS. At 335°, contact C2 opens, deenergizing relays R1, R2, R4, R5, and R12. Contacts R12a close and contacts R12b and R12c open, but relay R18 and solenoid SHS remain energized. The next character code sensed will cause the printer to print in the upper case.

To shift back to lower case position, the standard "letters shift" signal 12345 is used. If the sensing pins sense this combination in the tape, the relays R1—R5 are energized and, when contacts C2 close, a circuit is completed through wire 105, transferred contact R1c, contact R2d now closed, transferred contact R3e, contact R4f now closed, transferred contact R5f, coil of relay R11 to wire 101, energizing said relay. Contact R11a opens immediately, breaking the normal circuit through wire 104 before the contacts C3 close and thus preventing the code relays from being energized during this cycle. Contact R11b opens, breaking the holding circuit of relay R18. Contact R18b opens, dropping out the case shift solenoid SHS. At 335° the contact C2 opens, de-energizing the relay R11 and allowing the contact R11a to close, restoring the normal circuit through wire 104. The next character code sensed will cause the printer to print in the lower case.

It will be noted that the case shift signals operate in either code.

Carriage return mechanism

The carriage return code is the number 4 hole. When this is sensed in the tape, the relay R4 is energized and, when contacts C2 close, a circuit is completed through wire 105, normal contacts R1c, R2c, and R3d, transferred contact R4d, normally closed contact R5d, pick-up coil of relay R15, to wire 101, energizing said relay. The contact R15a closes, completing a circuit from wire 106 through normally closed contact R26c and the contact R15a, through the holding coil of relay R15. Contact R15c opens, disabling the circuit of the latch magnet LM. The armature 30 remains in latching position at the end of the cycle and the tape reader is prevented from continuing to read the tape, though the motor RM and cam contacts C1—C5 continue to operate. The energization of relay R4 also prepares the circuit to the code magnet M4 so that, when contact C3 closes at 144°, the normal circuit is completed through wire 104 to the code magnet M4, energizing said magnet. This causes the carriage return key CR of the printer to be operated.

Meanwhile, the contact R15d closed when the relay R15 was energized. This prepared a circuit for a cycling sequence, to provide time for the carriage return, which will now be described. When contact C2 opens near the end of the cycle in which the carriage return key is operated, the relay R4 is deenergized and contacts R4d return to normal position. On the next cycle, when contact C2 closes, a circuit is completed through wire 105, normal contacts R1c, R2c, R3d, and R4d, wire 108, contact R15d (now closed), wire 109, normal contacts R23b and R24b, coil of relay

R22, to wire 101, energizing said relay. Contact R22a closes, completing a holding circuit for relay R22, directly from the wire 109 and thence through the previously traced circuit including contact C2. Contact R22b closes, completing a circuit from wire 109, through the pick-up coil of relay R23, to wire 101, energizing said relay. Contact R23a closes, completing a holding circuit for relay R23 directly from wire 100, through wire 110, normal contact R24c, contact R23a, the holding coil of relay R23, to wire 101. Contact R23b transfers but without immediate effect, because contact R22c is open at this time.

Near the end of the cycle, contact C2 opens, breaking the holding circuit of relay R22, which drops out, restoring contacts R22c to their normally closed position. When contact C2 closes early in the next cycle, a circuit is completed from wire 109, through transferred contact R23b, contact R22c, now closed, the pick-up coil of relay R24, to wire 101, energizing said relay. Contact R24a closes, completing a secondary holding circuit for relay R23 through contact R23b to wire 109. Contact R24c transfers, completing a holding circuit for relay R24 direct from wire 110, through normally closed contact R26b and the holding coil of relay R24. The transfer of contact R24c breaks the holding circuit of relay R23 to the wire 110, but this relay remains energized through the above described secondary holding circuit. When contact C2 opens near the end of the cycle, relay R23 drops out, the relay R24 remaining energized.

When contacts C2 close early in the third cycle, a circuit is completed from wire 109, through normal contact R23b, transferred contact R24b, the coil of relay R26 to wire 101, energizing said relay. Contact R26a closes, completing a holding circuit for relay R26 from wire 108, through wire 111. Contact R26b opens, breaking the holding circuit of relay R24, which drops out. Contact R26c opens, breaking the holding circuit of relay R15, and which also drops out, restoring the contact R15c to its normal closed position, so that the latching magnet LM will be reenergized when the cam contact C5 closes near the end of the third cycle. About this time, the contact C2 opens, deenergizing the relay R26 and restoring the cycling circuits to normal condition.

Line feed circuit

In the type of printer disclosed carriage return and line feed are accomplished concurrently by operation of the carriage return key. If the carriage is in its fully returned position when the carriage return key is operated, a line feed alone takes place. The code employed includes the standard line feed signal 2, in addition to the standard carriage return signal 4, so that the messages can be monitored by machines requiring the line feed signal. The carriage return signal is always followed by a line feed signal, but a line feed signal may occur without a preceding carriage return signal, where plural line feed is required. It is necessary to prevent a line feed code from causing an operation of the carriage return key of the printer disclosed in this application, when the line feed code is preceded by a carriage return code; otherwise, there would be a double line feed where not intended. However, when a line feed code is not preceded by a carriage return code, it must operate the carriage return key. The means for accomplishing these functions will now be described.

When a carriage return code signal 4 is sensed 75

in the tape, it causes the operations previously described, including the energization of relay R15. Contact R15b closes, completing a circuit from wire 106, through said contact and pick-up 5 coil of relay R20, to wire 101, energizing said relay. Contact R20a closes a holding circuit from wire 106, through normally closed contact R21b, to the holding coil of relay R20. Contact R20b transfers, disabling the circuit of code magnet M2.

When a line feed signal 2 is sensed, after the previously described delay of three cycles, the code relay R2 is energized and, when contact C2 closes, a circuit is completed through wire 15 105, normal contact R1c, transferred contact R2c, normal contacts R3c, R4c, R5c, pick-up coil of relay R16, to wire 101, energizing said relay. The contact R16a closes, completing a circuit from wire 106, through normally closed contact 20 R26c and the holding coil of relay R16. Contact R16d closes, preparing a circuit for a three cycle delaying sequence, as previously described. Contact R16c opens, preventing the latch magnet from being energized at the end of the cycle, thus stopping the reading of the tape.

When contact C3 closes at 144°, the normal circuit is completed through wire 104, contact R2b, transferred contact R20b, wire 112, coil of relay R21, to wire 101, energizing said relay. Contact R21a closes, completing a holding circuit through holding coil of relay R20, holding said relay and thus continuing to disable the circuit of code magnet M2, until after the contact C3 opens at 250° in the first cycle. Contact R21b opens, breaking the holding circuit of relay R20 to the wire 106. Thus, the number 2 code signal is diverted through the relay R21, so as not to energize the code magnet M2, while a second delaying sequence is initiated to provide time for the carriage return and line feed operation of the printer.

If a line feed signal occurs not preceded by a carriage return signal, the contact R20b will be in normal position when the cam contact C3 closes and the code magnet M2 will be energized. This code magnet causes an operation of the keyless lever 76b (Fig. 4) and thus of the carriage return key CR. A line feed signal not preceded by a carriage return signal occurs only when the carriage is in its fully returned position. Operation of the carriage return key, therefore, causes only a line feed operation.

Summarizing the operation of the carriage return and line feed circuits, the carriage return code causes an operation of the carriage return key in either zone and stops the tape reader for three cycles. The line feed code following the carriage return code delays the reader for three more cycles, but does not cause an operation of the carriage return key. Thus, the reader is delayed for six cycles while the carriage is returning.

After the carriage is returned, if an additional line feed signal appears in the tape, it causes an operation of the carriage return key and stops the reader for three cycles.

Tabulation.—The TAB key on the typewriter is in zone 2. The tabulation code is 124. This is the same code as the letter *j* but the fact that tabulation is in zone 2 means that the relay R19 will be energized, preparing the circuit for code magnet M6. Accordingly, when the code 124 is sensed in the tape with the relay R19 energized, when the contact C2 is closed a circuit will be completed through wire 105, transfer contact R1c,

contact R_{2d} now closed, normal contact R_{3e}, contact R_{4e} now closed, normal contact R_{5e}, contact R_{19b} now closed, pick-up coil of relay R₁₇, to wire 101, energizing said relay. Contact R_{17a} closes, completing a holding circuit from wires 100, 106, through normally closed contact R_{26c}, contact R_{17a}, the holding coil of relay R₁₇, to wire 101. Contact R_{17c} opens, disabling the circuit of latch magnet LM. Contact R_{17d} closes, preparing a circuit for initiation of a three-cycle delay. When contact C₃ closes at 144°, the normal circuit is completed through wire 104 to code magnets M₁, M₂, M₄, M₆, energizing said magnets and causing the machine to tabulate. At 335° contact C₂ opens, disabling relays R₁, R₂ and R₄. When contact C₂ closes in the next cycle, a circuit is completed through wire 105, normal contacts R_{1c}, R_{2c}, R_{3d} and R_{4d} and wire 108 to the cycling circuits comprising relays R₂₂—R₂₆, with the result that three idle circuits follow as previously described. When relay R₂₆ is energized in the third cycle, contact R_{26c} opens and relay R₁₇ is deenergized, so that at the end of the cycle normal operations continue.

While there have been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a printing telegraph apparatus for translating into a printed message combinational code signals in a code based on a small number of different code positions, a printer having a keyboard comprising a larger number of keys than the possible number of different combinations of the code, and means responsive to the signals for selectively operating the keys of said keyboard, including zoning means responsive to certain zone shift signal combinations for routing succeeding signals to different zones of the keyboard comprising different groups of keys.

2. In a printing telegraph apparatus for translating into a printed message combinational code signals in a code based on a small number of different code positions, a printer having a keyboard comprising a larger number of keys than the possible number of different combinations of the code, and means responsive to the signals for selectively operating the keys of said keyboard, including zoning means for routing signals to different zones of the keyboard comprising different groups of keys, supervisory means controlling the operation of said zoning means adapted to remain stable in either of two different conditions, and means responsive to certain zone shift signal combinations for changing the condition of said supervisory means.

3. In a printing telegraph apparatus for translating into a printed message combinational code signals in a code based on a small number of code positions, a printer having a keyboard comprising a larger number of keys than the possible number of different combinations of the code, said keyboard being subdivided into different zones each including a different group of keys, a permutation mechanism for controlling the selective operation of said keys comprising a zoning permutation member for selecting the zone, and code permutation members corresponding to the respective

code positions for selecting the keys within a zone, means responsive to the signals for selectively controlling the operation of said code permutation members, and means responsive to certain zone shift signal combinations for controlling the operation of said zoning permutation member.

4. In a printing telegraph apparatus for translating into a printed message combinational code signals in a code based on a small number of different code positions, a printer having a keyboard comprising a larger number of keys than the possible number of different combinations of the code, said keyboard being subdivided into zones each including a different group of keys, a permutation mechanism for controlling the selective operation of said keys comprising a zoning permutation member for selecting the zone and code permutation members corresponding to the respective code positions for selecting the keys within a zone, electromagnetic devices for controlling said permutation members, energizing circuits for said electromagnetic devices, signal responsive means controlling the circuits of the electromagnetic devices pertaining to said code permutation members, relay means controlling the circuit of the electromagnetic device pertaining to said zoning permutation member, and means whereby said relay means is operated under control of said signal responsive means, on response of the latter to certain zone shift signal combinations.

5. A printing telegraph apparatus as described in claim 4, including means operated by said relay means for temporarily disabling the circuits of said electromagnetic devices.

6. A printing telegraph apparatus as described in claim 4, wherein the circuits of said electromagnetic devices include normally open contact means, means for closing said contact means at a predetermined time after response of said signal responsive means to a signal, and means operated by said relay means prior to the closing of said contact means for disabling the circuits of said electromagnetic devices for the duration of the response of said signal responsive means.

7. A printing telegraph apparatus as described in claim 4, wherein said relay means comprises a supervisory relay having a pick-up circuit and a self closing holding circuit, a zone shift relay for closing said pick-up circuit, a zone shift relay for opening said holding circuit, and means controlled by said signal responsive means for selectively energizing said zone shift relays, on response of said signal responsive means to the respective zone shift signals.

8. A printing telegraph apparatus as described in claim 4, wherein said relay means comprises a supervisory relay having a pick-up circuit and a self closing holding circuit, a zone shift relay for closing said pick-up circuit, a zone shift relay for opening said holding circuit, means controlled by said signal responsive means for selectively energizing said zone shift relays, on response of said signal responsive means to the respective zone shift signals, the circuits of said electromagnetic devices including normally open contact means, means for closing said contact means at a predetermined time after response of said signal responsive means to a signal, and means operated prior to the closing of said contact means upon energization of either of said zone shift relays for disabling the circuits of said electromagnetic devices for the duration of the response of said signal.

9. In a printing telegraph apparatus for trans-

lating into a printed message combinational code signals in a code based on a small number of different code positions, a printer having a keyboard comprising a larger number of keys than the possible number of different combinations of the code, said keyboard being subdivided into zones each including a different group of keys, a permutation mechanism for controlling the selective operation of said keys comprising a zoning permutation member for selecting the zone and code permutation members corresponding to the respective code positions for selecting the keys within a zone, electromagnetic devices for controlling said permutation members, energizing circuits for said electromagnetic devices, signal responsive means controlling the circuits of the electromagnetic devices pertaining to said code permutation members, a supervisory relay controlling the circuit of the electromagnetic device pertaining to said zoning permutation member, zone shift relays controlling the energization and deenergization of said supervisory relay, energizing circuits for said zone shift relays including means controlled by said signal responsive means for selectively preparing the same, the energizing circuits for said electromagnetic devices including normally closed contacts adapted to be opened by either of said zone shift relays, the energizing circuits of said zone shift relays and of said electromagnetic devices including normally open timing contacts, and means for closing said timing contacts sequentially, first those in the energizing circuits of said zone shift relays, then those in the energizing circuits of said electromagnetic devices.

10. In a printing telegraph apparatus for translating into a printed message signals recorded in a combinational code based on a small number of code positions, a printer having a keyboard comprising a larger number of keys than the possible number of combinations of the code, said keyboard being subdivided into zones each including a different group of keys, a permutation mechanism for controlling the selective operation of said keys comprising a zoning permuta-

tion member for selecting the zone and code permutation members corresponding to the respective code positions for selecting the keys within a zone, electromagnetic devices for controlling said permutation members, energizing circuits for said electromagnetic devices, a cyclically operable record reading device comprising code contacts operated in accordance with the code designations of the record, code relays having individual circuits controlled by the respective code contacts, zone shift relays, circuits for said zone shift relays including contacts controlled by said code relays so as to prepare said circuits selectively on response of said code relays to certain zone shift signal combinations, a supervisory relay controlled by said zone shift relays, a normal circuit comprising branches for the electromagnetic devices pertaining to said code permutation members including contacts operated by said code relays and a branch for the electromagnetic device pertaining to said zoning permutation member including a contact operated by said supervisory relay, said normal circuit including normally closed contacts operated by said zone shift relays and timing contacts closed by said record reader at a certain time in the cycle, the circuits of said zone shift relays including timing contacts closed by said record reader at an earlier time in the cycle than said first mentioned timing contacts.

11. In a page printer for printing messages in response to combinational code signals, a carriage return key lever, a line feed lever adapted to operate said carriage return key lever, permutation mechanism, means controlled by said permutation mechanism for selectively operating said levers, control means responsive to a line feed signal combination for causing said permutation mechanism to select said line feed lever, and control means responsive to a carriage return signal for causing said permutation mechanism to select said carriage return lever and for suppressing the operation of said first mentioned control means during the following signal period.
